US00D805523S

(12) **United States Design Patent** (10) Patent No.: **US D805,523 S**
(45) Date of Patent: **** Dec. 19, 2017**

(54) **SUPPORT APPARATUS**

- (71) Applicant: **Innovative Office Products, LLC**,
Easton, PA (US)
- (72) Inventors: **Stephen J. Bowman**, Allentown, PA
(US); **Peter J. Carrasquillo**, Easton,
PA (US); **Michael P. Smith**, Allentown,
PA (US); **Carl J. Hochberg**, Lehighton,
PA (US)
- (73) Assignee: **Innovative Office Products, LLC**,
Easton, PA (US)

(**) Term: **14 Years**

(21) Appl. No.: **29/493,274**

(22) Filed: **Jun. 6, 2014**

(51) LOC (10) Cl. **08-07**
(52) U.S. Cl.

CLAIM

The ornamental design for a support apparatus, as shown
and described.

DESCRIPTION

FIG. 1 is a perspective view of a support apparatus showing
our new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

(Continued)

The broken lines shown in FIGS. 1-7 illustrate portions of the support apparatus that form no part of the claimed design.

1 Claim, 7 Drawing Sheets
